PROCESS OF GRINDING GEARS

Arthur L. Stewart, Rochester, N. Y., assignor to
 Gleason Works, Rochester, N. Y., a corporation
 of New York

Application June 20, 1934, Serial No. 731,472

12 Claims. (Cl. 51—278)

The present invention relates to the grinding of gears in a generating process and particularly to the grinding of straight tooth bevel and hypoid gears.

There are two principal methods employed in grinding gears by the generating process and these methods distinguish from one another basically in the types of grinding wheels employed. In one method, the wheel used has a conical grinding surface which is inclined to the pitch surface of the gear in accordance with the pressure angle of the tooth surfaces to be ground and the tooth surfaces are generated by rotating the wheel on its axis and reciprocating it across the face of the gear while simultaneously producing a relative rolling movement between the wheel and gear as though the gear to be ground were rolling with a gear represented by the wheel. In the other method, the wheel used has a plane grinding surface and the wheel is so positioned relative to the gear to be ground that the plane surface of the wheel is inclined to the pitch surface of the gear in accordance with the pressure angle of the tooth surfaces. The grinding operation is effected by rotating the wheel on its axis while producing the necessary rolling movement. The wheel may or may not be reciprocated across the face of the gear, as desired. The wheel may be made of sufficiently large diameter to cover and grind the whole length of the tooth surfaces of the gear in which case no reciprocating motion is necessary.

Each of the above described methods has its advantages, and each its drawbacks. The conical surfaced wheel has theoretically only point contact at any instant with the tooth surfaces to be ground and therefore the feed of such a wheel can be quite coarse so that stock can be removed from the sides of the teeth of a gear quite rapidly with such a wheel without fear of "burning" the tooth surfaces. When this type of wheel is used, however, the quality of finish of the tooth surfaces depends primarily upon the number of strokes of the grinding wheel across the face of the gear while each tooth surface is being rolled out, and, even with extremely high stroke-speeds, it is not always possible to avoid so-called generating flats on the sides of the teeth being ground. The flat-sided wheel grinds a much smoother tooth surface and one without generating flats. The flat-sided wheel has, however, a line contact with the gear teeth and relatively fine feeds must be used in grinding with such a wheel if "burning" of the tooth surfaces is to be avoided.

The purpose of the present invention is to combine the advantages of the two processes while

eliminating the disadvantages of each. It is therefore the purpose of the present invention to provide a gear-grinding method which will be rapid and at the same time result in smooth tooth surfaces.

In all grinding, whether with a conical or a plane-sided wheel, it is customary to take one or more roughing grinds around the gear, removing stock, and then to set in and take a final finishing grind to secure a smooth tooth-surface finish. In the present invention, I propose to use the conical side of a wheel for rough grinding and the plane side of a wheel for the finish grinding. In the preferred embodiment of the invention, I use a double-sided wheel, one side being conical and the other side plane, and take the rough grinds with the conical side of the wheel and then set over and take the finish-grinds with the plane side of the wheel.

Preferably, two double-sided wheels are employed. For the rough-grinding, the two wheels will preferably be positioned to operate on opposite sides of the same tooth simultaneously. Their conical surfaces are inclined to the pitch surface of the gear in accordance with the pressure angles of the tooth surfaces to be ground and the grinding is effected by reciprocating the wheels across the face of the gear while producing the required rolling generating motion. The directions of the reciprocating motions will depend on the lengthwise directions of the tooth surfaces. For finish-grinding, the wheels are repositioned with the plane surfaces of the wheels inclined to the pitch surface of the gear in accordance with the pressure angles on the opposite sides of the teeth and preferably so positioned that the plane surfaces operate on opposite sides of alternate teeth of the gear. For tapered gears, the angles of convergence of the paths of the wheels must also be readjusted between the rough and finish grinding operations, for the angle of convergence of the tool paths, when the wheels are operating on opposite sides of the same teeth is much less than the angle of convergence of the tool paths, when the wheels are operating on opposite sides of different teeth. In the finish-grinding, the wheels may be reciprocated if desired, but if their diameter is large enough the reciprocating movement can be omitted during the finish grinding operation.

The advantages of the present process are manifold. First, the use of the conical side of the wheel during rough-grinding permits of removing stock very rapidly without danger of "burning".

and because only a thin film of metal is left for the finish-grind, the plane side of the wheel will effect its operation, too, without danger of "burning" and through the joint use of the two wheels 5 there will be obtained highly finished tooth surfaces free of flats and in a minimum of operating time. Second, the speed of reciprocation of the wheel can be very materially reduced over that previously employed in grinding with a conical 10 wheel because the smoothness of finish is no longer dependent on the number of strokes of the wheel across the face of the gear during the rolling out of the tooth profiles. Third, as against any previous process of grinding gears with two 15 wheels, the present method is most economical in the matter of wheels, since it makes use of both sides of a wheel. Fourth, this process reduces the possibility of errors in tooth spacing, since the first and last teeth which are rough-ground 20 are not, due to the set-over of the wheels, the same teeth as are first and last finish-ground. Finally, one of the added advantages of the present invention is that, with but few, if any, alterations, existing machines can be employed in grinding 25 gears according to this invention. Thus, the invention has been illustrated in connection with the grinding of straight bevel gears on a grinder of the type covered by the pending application of Eivind Finsen, Serial No. 603,541, filed April 6, 30 1932. Provision for sufficient angular adjustment of the grinding wheel spindles to take care of the changes in positions of the wheels required in order to grind the correct pressure angles with either the conical sides or the plane sides of the 35 wheels is all that is required to make this particular machine suitable for use in grinding gears according to the present invention.

The principal objects of the present invention have now been mentioned. Other objects of the 40 invention will appear hereinafter from the specification and from the recital of the appended claims.

In the drawings:

Fig. 1 is a fragmentary end view showing the 45 positions of the grinding wheels and gears in a rough-grinding operation according to the present invention;

Fig. 2 is a corresponding view showing the relative positions of the wheels and gear during finish 50 grinding;

Fig. 3 is a view at right angles to Fig. 1 and further illustrating the positions of the grinding wheels and gear during the rough-grinding operation, the gear ground being a straight bevel gear, 55 some of whose teeth are shown in section and whose outline is indicated in dotted lines; and

Fig. 4 is a view taken at right angles to Fig. 2, and further illustrating, by contrast with Fig. 3, the 60 positions of the grinding wheels in the finish grinding operation.

In the above views, the machine parts shown are parts of a machine such as has been described in the Finsen et al. application above mentioned.

In the drawings, G designates a bevel gear 65 whose tooth surfaces are to be ground and 5 and 6 denote, respectively, a pair of grinding wheels which are to be employed in the grinding of the tooth surfaces of this gear. The wheels are provided on one side with truncated conical grinding 70 surfaces 7 and 8, respectively, and on their other sides with plane grinding surfaces 9 and 10, respectively, and the wheels are suitably secured as by means of nuts 11, to spindles 12. The spindles are journaled on anti-friction bearings 75 13 in heads 14 that are adjustably mounted on

tool-slides 15. The tool-slides are mounted, as shown, to reciprocate in tool-arms 16 and 17, respectively. These arms are angularly adjustable, to determine the angle of convergence of the paths of travel of the wheels. The arms adjust angularly about an axis x, and their angular adjustment can be effected by rotation of the screw shaft 18 which threads into the two heads 19 and 20 that are swivelly connected to studs which thread into the arms 16 and 17. The slides are reciprocated by rotation of the crank 22 which is connected by the crank-arm 23, link 24, actuating member 25, bolts 26 and nuts 27 with the slides 15. 5

The grinding wheel spindles have pulleys 29 secured to them and are driven through these pulleys and belts 30 from motors mounted on the arms 16 and 17 or from any suitable source of power. 15

In the practice of my invention, the gear is, of course, first rough-ground. For this purpose, the grinding wheels 5 and 6 are adjusted relative to the gear G so that their conical surfaces 7 and 8, respectively, engage opposite sides 37 and 38, respectively, of a tooth 40 of the gear and so that these conical operating surfaces 7 and 8 are inclined to the pitch surface of the gear at the angle required to produce correct pressure angle on the sides 37 and 38, respectively, of the teeth of the gear. This is shown in Fig. 1. 20 25 30

The arms 16 and 17 are also adjusted by the screw 18 in order to adjust the longitudinal paths of travel of the slides 15 and of the grinding wheels in conformity with the longitudinal direction of the tooth surfaces to be ground. This is clearly shown in Fig. 3, where the slides 15 are shown as adjusted so that the grinding wheels 5 and 6 will reciprocate along paths 41 and 42, respectively, which converge in a point x and are inclined to one another at the same angle as the angle of convergence of the sides 37 and 38 of the teeth of the tapered gear G being ground. 35 40 45

The rough-grinding operation is effected by rotating the grinding wheels 5 and 6 on their axes and simultaneously reciprocating the wheels across the face of the gear G while producing a relative rolling motion between the wheels and gear to generate the tooth profiles. For bevel gears, the rolling motion may be produced through the mechanism forming part of the machine of the Finsen et al application. When the sides of a tooth have been ground, the wheels are withdrawn from engagement with the gear and the gear is indexed as in the ordinary operation. The wheels are then moved into engagement with the next tooth of the gear and this is ground and the operation proceeds as before until all of the teeth have been rough-ground. 50 55

There may be more than one rough-grinding operation, but the wheels will simply be fed laterally between successive rough-grinding operations in order to remove more stock. 60 65

After the rough-grinding operation has been completed, the wheels are readjusted relative to the gear as shown in Figs. 2 and 4. The conical operating surfaces of the wheels are moved out of operative position and the plane sides 9 and 10 of the wheels are brought into operative position. This is done by spreading the wheels far enough apart so that their conical surfaces 7 and 8, respectively, no longer engage opposite sides 37 and 38 respectively, of a tooth 40 of the gear, but their plane sides 9 and 10, respectively, are brought into engagement with opposite sides 38 and 37, respectively, of alternate teeth 39 and 70 75 80 85 90 95

41, respectively, of the gear. The wheels are also readjusted relative to one another so that their axes are inclined to one another at the angle required to incline the plane sides 9 and 10 of 5 the wheels to the pitch surface of the gear to produce the required pressure angles on the finished tooth surfaces. The arms 16 and 17 of the machine are also readjusted to change the angle of convergence of the wheel paths as required by reason of the fact that the wheels are now to grind opposite sides of alternate teeth 10 of the gear. To obtain the first described angular adjustment in the Finsen machine, the wheel heads 14 may be mounted upon plates (not shown) that are adjustable angularly on the tool slides 15, as will be obvious to anyone skilled in the art.

For the finish-grinding, the wheels are rotated on their respective axes and simultaneously a 20 relative rolling motion is produced between the wheels and gear to generate the tooth profiles. If the wheels are of sufficiently large diameter, they do not have to be reciprocated across the face of the gear, but will have their planes of 25 action simply inclined to one another at the angle corresponding to the angle between the sides 38 and 37 of alternate teeth of the gear and defined by the lines 45 and 46 in Fig. 4. If desired, however, the wheels may actually be reciprocated along the paths 45 and 46.

When the sides 37 and 38, respectively, of alternate teeth 39 and 41 have been ground, the wheels will be withdrawn from operating position and the gear indexed. The wheels will 35 then be moved back into engagement with the gear to grind other pairs of opposite side tooth surfaces of the gear and the alternate grinding and indexing will proceed until all of the teeth have been finish-ground.

40 Due to the fact that in the finishing operation the wheels grind upon opposite sides of alternate teeth of the gear whereas in the roughing operation they grind upon opposite sides of the same tooth, any errors in spacing of the teeth which 45 may occur by reason of wear of the wheels in the rough-grinding operation will be compensated for and eliminated in the finish-grinding operation. This results from the fact that the teeth which are, respectively, the first and last 50 to be ground in the rough-grinding operation are not the same teeth which are ground first and last, respectively, in the finish grinding operation.

For the purposes of clearness in disclosure, the 55 invention has been described in connection with the grinding of straight bevel gears on a particular type of straight bevel gear grinder. It will be obvious, however, that the invention is not limited to practice with this machine. The invention may be applied equally to the grinding of spur gears as well as to the grinding of tapered gears and any suitable type of machine may be employed for either purpose with any suitable type of generating mechanism.

65 It is to be noted that in the grinding of spur gears, it is not necessary, of course, to change the directions of the paths of reciprocation of the grinding wheels between the rough and finish 70 grinding, for whether straight or helical spur gears are being ground the wheels reciprocate in parallel paths both in the roughing and in the finish-grinding operations. The wheels are simply spaced further apart in the finish-grinding in order to grind opposite sides of spaced (alternate) teeth of the gear.

In general, it may be said that the invention is capable of various modifications and uses, and this application is intended to cover any variations, uses, or adaptations of the invention following, in general, the principles of the invention and including such departures from the present disclosure as come within known or customary practice in the gear art and as may be applied to the essential features hereinbefore set forth and as fall within the scope of the invention 10 or the limits of the appended claims.

Having thus described my invention, what I claim is:

1. The method of grinding the tooth surfaces of a gear which comprises, first, rough-grinding 15 the tooth surfaces with a grinding wheel having a conical operating surface by reciprocating the wheel across the face of the gear while rotating the wheel on its axis and simultaneously producing a relative rolling generating movement 20 between the wheel and the gear, and then finish-grinding the same tooth surfaces with a grinding wheel having a plane operating surface by rotating the wheel on its axis while simultaneously producing a relative rolling generating movement 25 between the wheel and the gear.

2. The method of grinding the tooth surfaces of a gear which comprises, first, rough-grinding the tooth surfaces with a grinding wheel having a conical operating surface by reciprocating the 30 wheel across the face of the gear while rotating the wheel on its axis and simultaneously producing a relative rolling generating movement between the wheel and the gear, and then finish grinding the same tooth surfaces with a grinding 35 wheel having a plane operating surface by reciprocating the wheel across the face of the gear while rotating the wheel on its axis and simultaneously producing a relative rolling generating 40 movement between the wheel and gear.

3. The method of grinding the tooth surfaces of a gear which comprises employing a wheel having a conical surface on one side and a plane surface on the other, rough-grinding the tooth surfaces with the conical side of the wheel by 45 reciprocating the wheel across the face of the gear while rotating the wheel on its axis and producing a relative rolling generating movement between the wheel and gear, repositioning the wheel relative to the gear, and then finish-grinding the tooth surfaces with the plane side of the 50 wheel in a rolling generating operation.

4. The method of grinding the tooth surfaces of a gear which comprises employing a grinding 55 wheel having a conical surface on one side and a plane surface on the other, first rough-grinding the tooth surfaces by positioning the conical side of the wheel in operative relation with the tooth surfaces and reciprocating the wheel across the face of the gear while producing a relative rolling movement 60 between the wheel and the gear, then finish-grinding the same tooth surfaces by positioning the plane side of the wheel in operative relation with the tooth surfaces and reciprocating the wheel across the face of the 65 gear while rotating the wheel on its axis and producing a relative rolling movement between the wheel and the gear.

5. The method of grinding a gear which comprises employing a pair of grinding wheels, each 70 of which has a conical grinding surface on one side and a plane grinding surface on the other side, first positioning said wheels so that the conical sides thereof are in operative engagement, respectively, with opposite sides of the same tooth 75

- of the gear, and rough-grinding the tooth surfaces by reciprocating the wheels across the face of the gear while rotating the wheels on their axes and producing a relative rolling generating movement between the wheels and the gear, then repositioning the wheels so that their plane grinding surfaces are in operative engagement, respectively, with opposite sides of spaced teeth of the gear and rotating the wheels on their axes while 5 producing a relative rolling generating movement between the wheels and gear.
6. The method of grinding a gear which comprises employing a pair of grinding wheels, each of which has a conical grinding surface on one 10 side and a plane grinding surface on the other, first positioning said wheels so that the conical sides thereof are in operative engagement, respectively, with the sides of the same tooth of the gear, and rough-grinding the tooth surfaces by 15 reciprocating the wheels across the face of the gear while rotating the wheels on their axes and producing a relative rolling generating movement 20 between the wheels and the gear, then repositioning the wheels so that their plane grinding surfaces are in operative engagement, respectively, with opposite sides of spaced teeth of the gear and reciprocating the wheels across the face of the gear while rotating them on their axes and 25 producing a relative rolling generating movement 30 between the wheels and gear.
7. The method of grinding a gear which comprises employing a pair of grinding wheels, each of which has a conical grinding surface on one side and a plane grinding surface on the other, first positioning said wheel so that the conical sides thereof are in operative engagement, respectively, with opposite sides of the same tooth of the gear, and rough-grinding the tooth surfaces by reciprocating the wheels across the face 35 of the gear by rotating the wheels on their axes and producing a relative rolling generating movement between the wheels and gear, then repositioning the wheels so that their plane grinding surfaces are in operative engagement, respectively, with opposite sides of alternate teeth of the gear and rotating the wheels on their axes while producing a relatively rolling generating movement 40 between the wheels and the gear.
8. The method of grinding a gear which comprises employing a pair of grinding wheels, each of which has a conical grinding surface on one side and a plane grinding surface on the other, first positioning said wheels so that the conical sides thereof are in operative engagement, respectively, with opposite sides of the same tooth of the gear, and rough grinding the tooth surfaces by reciprocating the wheels across the face 45 of the gear while rotating the wheels on their axes and producing a relative rolling generating movement between the wheels and the gear, then repositioning the wheels so that their plane grinding surfaces are in operative engagement, respectively, with opposite sides of alternate teeth of the gear, and reciprocating the wheels across 50 the face of the gear while rotating them on their axes and producing a relative rolling generating movement between the wheels and the gear.
9. The method of grinding a straight tooth tapered gear which comprises rough grinding the tooth surfaces of the gear with a grinding wheel having a conical grinding surface by positioning 55 said wheel so that its conical surface is inclined to the pitch surface of the gear at an angle determined by the pressure angle of the tooth surfaces to be ground and reciprocating the wheel in a longitudinal path determined by the lengthwise direction of the gear teeth while rotating the wheel on its axis and producing a relative rolling motion between the wheels and gear, and then finish grinding the same tooth surfaces with a grinding wheel having a plane grinding surface by positioning said wheel so that its plane surface is inclined to the pitch surface of the gear at an angle determined by the pressure angle of the tooth surfaces to be ground and so that said plane surface is inclined to the axis of the gear in correspondence with the longitudinal direction of the tooth surfaces, and rotating the wheel in engagement with the gear while producing a relative rolling movement between the wheel and gear.
10. The method of grinding a straight tooth tapered gear which comprises rough grinding the tooth surfaces of the gear with a grinding wheel having a conical grinding surface by positioning 10 said wheel so that its conical surface is inclined to the pitch surface of the gear at an angle determined by the pressure angle of the tooth surfaces to be ground and reciprocating the wheel in a longitudinal path determined by the lengthwise direction of the tooth surfaces while rotating the wheel on its axis and producing a relative rolling motion between the wheel and gear, and then finish grinding the same tooth surfaces with a grinding wheel having a plane grinding surface by positioning said wheel so that its plane surface is inclined to the pitch surface of the gear at an angle determined by the pressure angle of the tooth surfaces to be ground, and reciprocating said wheel across the face of the gear in a longitudinal path determined by the lengthwise direction of the tooth surfaces while rotating the wheel on its axis and producing a relative rolling motion between the wheel and gear.
11. The method of grinding a straight tooth tapered gear which comprises employing a pair of grinding wheels each of which has a conical grinding surface on one side and a plane grinding surface on the other, rough grinding the tooth surfaces of the gear by positioning the conical sides of the wheels in operative engagement with opposite sides of the same tooth of the gear with their conical surfaces inclined to the pitch surface of the gear in accordance with the pressure angle of the tooth surfaces to be ground, and reciprocating the wheels across the face of said gear in longitudinal paths converging in accordance with the angle of convergence between opposite sides of a tooth of a gear while rotating the wheels on their axes and simultaneously producing a relative rolling motion between the wheels and gear, and then finish grinding the tooth surfaces of the gear by repositioning the grinding wheels so that their plane sides are in engagement, respectively, with opposite tooth sides of alternate teeth of the gear with the plane sides of the wheels inclined to the pitch surface of the gear in accordance with the pressure angles of the tooth surfaces to be ground with the planes of said wheel-surfaces inclined to one another in accordance with the angle of convergence of the tooth sides being ground and rotating the wheels on their axes while producing a relative generating rolling movement between the wheels and gear.
12. The method of grinding a straight tooth tapered gear which comprises employing a pair of grinding wheels each of which has a conical grinding surface on one side and a plane grinding 75

surface on the other, rough-grinding the tooth surfaces of the gear by positioning the conical sides of the wheels in operative engagement with opposite sides of the same tooth of the gear with the conical sides of the wheels inclined to the pitch surface of the gear in accordance with the pressure angles of the tooth surfaces to be ground, and reciprocating the wheels across the face of the gear in longitudinal paths converging in accordance with the angle of convergence between opposite sides of the teeth of the gear while simultaneously producing a relative rolling motion between the wheels and the gear, and then finish-grinding the tooth surfaces of the gear by repositioning the grinding wheels so that their plane sides are in engagement, respectively, with opposite tooth sides of alternate teeth of the gear with the plane sides of the wheel inclined to the pitch surface of the gear in accordance with the pressure angles of the tooth surfaces to be ground and with the planes of said surfaces inclined to one another in accordance with the angle of convergence of the tooth sides being ground, and reciprocating the wheels across the face of the gear in paths converging correspondingly while rotating the wheels on their axes and simultaneously producing a relative rolling motion between the wheels and gear.

ARTHUR L. STEWART. 15
